(57) **CLAIM**

I claim the ornamental design for a wine aerator, as shown and described.

DESCRIPTION

FIG. 1 — is a front perspective view of a wine aerator showing my new design.

FIG. 2 — is a side elevational view. The opposite side appearing identical.

FIG. 3 — is a top view thereof; and,
FIG. 4 — is a bottom view thereof.

1 Claim, 2 Drawing Sheets

FIG.1.

FIG.2.

FIG. 3.

FIG. 4.
